UNITED STATES PATENT OFFICE

LEWIS F. BROWN, OF HAMMOND, NEBRASKA.

LOADING APPARATUS.

1,216,206.

Specification of Letters Patent. Patented Feb. 13, 1917.

Application filed October 4, 1915. Serial No. 54,016.

To all whom it may concern:

Be it known that I, LEWIS F. BROWN, a citizen of the United States, residing at Hammond, in the county of Rock and State 5 of Nebraska, have invented certain new and useful Improvements in Loading Apparatus, of which the following is a specification.

This invention relates to loading apparatus and more particularly to a loader 10 designed for use in loading manure or dirt from the ground level into a wagon or other vehicle in which it is to be conveyed.

It is one aim of the present invention to so construct the loader that the dumping 15 platform thereof will be automatically dumped when it has been elevated to the proper distance above the ground surface and will be automatically returned to receiving or horizontal position in its lower- 20 ing movement.

Another aim of the invention is to provide novel means for steadyng the dumping platform as the same is elevated and lowered and for firmly supporting the platform 25 in its movement from horizontal to dumping position so that the load carried thereby will be directed with certainty into the wagon box which is to receive it and there will be no likelihood of scattering of the 30 material comprising the load.

In the accompanying drawings:

Figure 1 is a perspective view of a loading apparatus embodying the present invention.

Fig. 2 is a vertical front to rear sectional 35 view therethrough.

Fig. 3 is a side elevation of a portion of the pawl and ratchet mechanism illustrating one position of the pawl in full lines and another position in dotted lines.

Fig. 4 is a perspective view of the engaging end of the pawl.

Fig. 5 is a side elevation illustrating the dumping platform in raised position just before it is tilted.

Fig. 6 is a view similar to Fig. 5 illustrating the platform in dumped position.

The apparatus includes a supporting frame structure which may be of any suitable construction but is here shown as comprising a base 1 upon which are mounted uprights 2, the uprights being braced by inclined brace members 3 secured at their upper ends to the uprights and at their lower ends to the said base 1. The numeral 45 4 indicates in general the receiving or loading platform of the structure and this plat-

form is supported upon sills 5 and is inclined downwardly in a direction away from the uprights 2. Side sills 6 are arranged and supported at their ends upon the sills 5. Other braces 7 are secured at their upper ends to the uprights 2 and at their lower ends to the sills 6. At their upper ends the uprights 2 are connected by cross beams 8 which complete the frame structure. 60

The dumping platform comprises a platform proper indicated by the numeral 9 and provided with side boards 10 and a front board 11. Said platform prior to loading thereof is positioned as shown in 70 Figs. 1 and 2, upon the base 1 and between the lower ends of the uprights 2 with its front board 11 extending close to and lying against the rear edge of the loading platform 4. The means provided for raising 75 and lowering the dumping platform 9 includes a winding shaft 12 which is mounted in suitable bearings 13 supported upon the cross beams 8 at the upper ends of the uprights 2 and an intermediate bearing 14 supported upon the said beams 8 between their ends. Chains 15 are connected in any suitable manner to the shaft 12 at opposite sides of the bearing 14 and are led downwardly and connected by means of branch chains 80 16 to the dumping platform 9 at the ends of the latter, the point of connection being such that when the shaft 12 is rotated so as to wind the chains 15 thereon, the platform 9 will be substantially evenly balanced and 85 will retain its horizontal position as it is raised and lowered. In order that the shaft 12 may be rotated, a drum 17 is secured upon the said shaft at one end thereof and wound upon this drum 17 is a cable 18 which 90 is led downwardly from the drum and through a block 19 connected to the base 1. The cable is provided at its end with any suitable form of hook or clevis 20 in order that a draft animal may be connected with 95 the cable for the purpose of unwinding the same from the drum 17 and thereby imparting rotary motion to the shaft 12. Pins 21 project from the side boards 10 of the platform and bear against the rear sides of 100 the uprights in the manner clearly shown in Figs. 1 and 5 of the drawings as the platform ascends or descends. An arm 22 is secured to each of the uprights 2 and these arms extend rearwardly at a slight 105 angle toward each other from the said uprights and have their rear end portions

turned to extend directly rearwardly to constitute abutments indicated by the numeral 23. The arms 22 are braced by means of arms 24 which extend downwardly from 5 their secured ends and are secured to the respective arms 22 near the ends 23 as indicated at 25 and terminate in hooked fingers 26 which lie below the said ends 23, the bills of the hooks 26 being presented toward the 10 lower edges of the abutment portions 23 but spaced therefrom a sufficient distance to permit of the passage between these parts of stop pins 27 projecting laterally from the side boards 10 of the dumping platform 9.

Referring now particularly to Figs. 5 and 6 of the drawings, it will be observed that as the platform 9 is moved upwardly, the pins 21 ride against the rear sides of the 20 uprights 2 until the platform reaches the position shown in Fig. 5 when the stop pins 27 will have engaged against the abutments 23. The upward movement of the flexible suspension members 15 continuing, the platform 25 will be caused to tilt by reason of the engagement of the pins 27 with the abutments and the said pins will ride under the abutments toward the vertical plane of the suspension means. This movement of the 30 pins 27 is arrested by the hook members 26 whereupon the pins 21 recede from engagement with the uprights 2 by reason of the suspension members tilting to assume positions in a plane passing through the winding shaft and the pins 27. The platform will, consequently, be tilted to such an extent that its contents will be dumped and will be deposited in the spreader or other vehicle provided to receive it. It may sometimes happen that the shifting of the load will be accompanied by a slackening of the tension in the cable 18 so that the platform tends to swing forwardly and downwardly. This movement carries the pins 27 into engagement with the hook members 26 so that the downward movement of the rear side of the platform will be arrested and if the pawl, presently described, be shifted into engagement with the pulley 17, so as to hold 45 the same against rotation, the winding shaft will be held stationary and the platform will be supported in tilted position by the pawl, the suspension means, the pins 27 and the hooks 26 so that all particles of the load 50 which may tend to adhere to the platform may be scraped therefrom as will be readily understood. If this slight dropping operation, during the dumping operation, does not occur, the tension of the suspension 55 members will hold the pins 27 against the abutments 23 and the hook members 26. After the entire load has been discharged, the platform will, of course, be lowered to receive another load and the initial lowering 60 movement will carry the pins 27 into en-

gagement with the bills of the hook members 26 so that the pins will rest in said hooks. The continued unwinding of the suspension means will then cause the platform to swing toward a horizontal position with the pins 27 as a center, thereby bringing the pins 21 against the frame and the impact of the pins 21 against the frame will cause the pins 27 to ride out of the hook members so that the platform may then be lowered while in a horizontal position. As shown clearly in Fig. 5, the distance between the pins 21 and 27 is greater than the horizontal distance between the uprights and the hook members. When the movement of the tilted platform toward a horizontal position brings the pins 21 against the frame, the greater weight of the platform is exerted through the pins 21 and the impact of the pins against the frame is sufficient to cause the pins 27 to ride up and out of the hook members. It will be noted that the bill or extremity of the hook member is not parallel with the shank of the same so that the pin 27 may be readily dislodged therefrom although it will seat therein and will aid in supporting the platform if undisturbed.

The pawl and ratchet mechanism, above referred to, includes a bar 28 which is pivoted at its lower end, as at 29, upon one of the side sills 6 and extends upwardly through a guide yoke 30 secured upon the adjacent brace 7. This bar is provided at its upper end with a pawl comprising a plate 31 secured in any suitable manner to one side of the said bar 28 and provided with a shoulder 32 and a curved finger 33. Normally the pawl rests by gravity in the path of movement of pins 34 arranged in an annular series upon one side or end of the winding drum 17, these pins serving the same purpose as the teeth of a ratchet. The finger 33 serves by reason of engagement with the pin 34, to limit the movement of the bar 28 in the direction of the said teeth and the shoulder 32 serves as an abutment against which the pins may engage for the purpose of preventing backward rotation of the drum when the dumping platform has been elevated to the desired point. In order that the bar 28 may be held out of position for coöperation with the ratchet pins 34 upon the winding drum a detent block 35 is disposed against the rear side of the bar 28 and is supported by one arm 36 of an angle lever, the other arm 37 of which constitutes a handle through the medium of which the lever may be rocked to move the block 35 upwardly or downwardly against the rear side of the bar 28. The block 35 is provided at its under side with a lug 38 located next adjacent the bar 28 and the under side of the block constitutes a shoulder 39 which serves a purpose which will now be ex-

plained. When the block 35 is in the position shown in full lines in Fig. 3 of the drawings this lug 38 is located above the upper end of the guide yoke 30 and the 5 bar 28 rests against the upper end of the said yoke and in this position is active. When it is desired to render the pawl bar inactive, the bar is swung forwardly to the dotted line position shown in the said Fig. 10 3 and the lever 37 is rocked so as to lower the block 35. In this movement of the block its lug 38 will be brought into position between the rear side of the bar 28 and the upper end of the yoke 30 with the shoulder 15 39 resting upon the said upper end of the yoke and limiting the downward movement of the block. By reason of the engagement of the lug 38 between the bar and the upper end of the yoke, the bar 28 will be held in 20 inactive position or, in other words, in position with its pawl 31 out of engagement and out of the path of movement of the ratchet teeth 34 upon the winding drum.

Having thus described the invention, what 25 is claimed as new is:

1. A loader of the class described comprising a frame, a dumping platform arranged within the frame, suspension means for the platform operable to elevate and 30 lower the same, an abutment upon the frame, a hook member located in juxtaposition to the abutment, an element upon the platform arranged to engage with said abutment on the upward movement of the platform 35 whereby to effect tilting of the same and adapted to subsequently rest in the said hook member whereby to assist the suspension means in supporting the platform in dumping position, and means for automatically disengaging the said element from the said hook member to permit return of

the platform to the horizontal position and downward movement of the same.

2. A loader comprising a dumping platform, suspension means for the platform 45 operable to elevate and lower the same, an abutment, a pendent hook member located in juxtaposition to the abutment, an element upon the platform arranged to engage with said abutment whereby to cause tilting 50 of the platform and adapted to rest in said hook member whereby to assist the suspension means in supporting the platform in dumping position, a fixed member, and an abutment projecting from the platform and 55 arranged to ride against the fixed member in the lowering movement of the platform whereby to so displace the platform as to disengage the first-mentioned element from the hook member.

3. In a loader of the class described, a frame having spaced uprights, a dumping platform arranged within the frame, suspension means for the platform operable to raise and lower the same, an abutment 60 projecting from the frame, a hook member depending from the abutment near the end thereof, a pin upon the platform arranged to engage against said abutment on upward movement of the platform whereby to cause 65 tilting movement of the platform and upon further upward movement of the platform to ride under the abutment to the hook member, and an abutment pin projecting from the platform and arranged to ride 70 against one of the said uprights in the movement of the platform whereby to hold the first-mentioned pin clear of the said hook member.

In testimony whereof, I affix my signature.

LEWIS F. BROWN. [L.S.]
